UNITED STATES PATENT OFFICE.

FRIEDRICH WETTE, OF KOBLENZ, GERMANY.

RUBBER SOLE FOR SHOES AND THE LIKE.

1,032,640.

Specification of Letters Patent. Patented July 16, 1912.

Application filed June 13, 1911. Serial No. 632,880.

To all whom it may concern:

Be it known that I, FRIEDRICH WETTE, merchant, a subject of the King of Prussia and German Emperor, residing at Koblenz on-the-Rhine, in the Kingdom of Prussia and German Empire, have invented certain new and useful Improvements in Rubber Soles for Shoes and the Like, of which the following is a specification.

10 My invention relates to improvements in rubber-soles for shoes and the like.

The improved rubber-sole forming the object of my invention comprises a suitably shaped rubber-frame, an inner flange of small thickness in one piece with said rubber-frame and in one line with the surface of the rubber-frame which is to lie against the sole of the shoe and the like, means, such as leather-strips let into said rubber-frame, for fastening the rubber-frame by means of pegs and the like to the leather-sole of the shoe and the like, and a middle leather-piece adapted to fill out the free inner space or outcut of said rubber-frame 25 and to rest against said inner flange of the rubber-frame, said middle leather-piece being fastened to the leather-sole of the shoe by suitable means, such as pegs and the like. This arrangement enables even an unskilled 30 person to easily and readily connect rubber-soles to shoes with but a small quantity of pegs or the like.

In the accompanying drawing forming a part of this specification and in which similar letters refer to corresponding parts throughout the several views, Figure 1 is a view from below of the new rubber-frame, according to my invention. Fig. 2 is a longitudinal section of same on line A—B of Fig. 1. Fig. 3 is a cross-sectional view of the rubber-frame on line C—D of Fig. 1. Fig. 4 is a longitudinal section of a shoe provided with the new arrangement.

The outer part of my improved rubber-45 sole is composed of a frame *a* of suitable shape, said frame having a middle free space or outcut of suitable configuration, in order to save expensive rubber material and to allow of a leather filling-piece or partial 50 sole being inserted. In one piece with the inner outcut or edge of the rubber-frame is made a flange *b* of small thickness and

breadth, said flange *b* lying in the same level as the surface of the rubber-frame which is to rest against the sole of the shoe 55 and the like. In cavities of suitable dimensions formed in the rubber-frame *a*, small leather-strips *c* are let in, these leather strips being intended to stiffen the rubber, *i. e.* to allow of pegs *d* and the like being driven 60 through, in order to fasten the rubber-frame to the shoe without the possibility of the rubber being damaged, inasmuch as rubber, as a matter of fact, does not withstand the lateral tearing action of pegs directly inserted or driven into it, such tearing action 65 always takes place, when the foot presses on the sole of the shoe. In this way, the leather-strips *c* afford a protection of the leather and augment the resistance and durability 70 of the whole connection. Further, in the free inner space or outcut of the rubber-frame is inserted a leather-piece *e* shown in dotted lines in Fig. 3 and in full lines in Fig. 4. This leather-piece, partial sole or 75 filler *e* has the same form or configuration as the inner free space or outcut of the rubber-frame *a*, and consequently is provided at its edge with a shoulder corresponding exactly to the inner flange-part *b* of the 80 rubber-frame *a*. On being introduced into the free space of the rubber-frame the leather-piece or filler *e* rests with its outer portion against the flange *b* of the rubber-frame and presses said flange against the 85 corresponding part of the leather-sole of the shoe.

The leather-piece, partial sole or filler *e* is fixed in position by suitable means, such as pegs and the like, driven through the edge 90 or rim of said part *e* and through the flange *b* of the rubber-frame *a*.

Having thus described my invention, what I claim and desire to secure by Letters Patent of the United States is:—

A rubber-sole, comprising a suitably shaped rubber-frame, an inner flange of small thickness and breadth in one piece with said rubber-frame and in the same level as the surface of the rubber-frame 100 which is to lie against the sole of the shoe and the like, a series of leather-strips let in up to a certain depth into said rubber-frame and adapted to be fastened to the

leather-sole by means of pegs and the like, and a leather filling-piece of the same shape as the inner edge of the rubber-frame and having at its outer edge a shoulder corresponding to said inner flange of the rubber-frame, said filling-piece being to rest against said flange of the rubber-frame and to be fastened to the sole by suitable means, such

as pegs and the like, substantially as described.

In testimony whereof I affixed my signature in presence of two witnesses.

FRIEDRICH WETTE.
